J. T. SIBLEY,
DIAPHRAGMATIC SOUND PRODUCER.
APPLICATION FILED SEPT. 5, 1916.

Patented July 2, 1918.

Inventor:
James F. Sibley,
By his Attorney,
Geo. W. Munn,

UNITED STATES PATENT OFFICE.

JAMES T. SIBLEY, OF NEW YORK, N. Y.

DIAPHRAGMATIC SOUND-PRODUCER.

1,270,884.

Specification of Letters Patent.

Patented July 2, 1918.

Application filed September 5, 1916. Serial No. 118,333.

To all whom it may concern:

Be it known that I, JAMES T. SIBLEY, a citizen of the United States, and a resident of the borough of Manhattan, city, county, and State of New York, have invented certain new and useful Improvements in Diaphragmatic Sound-Producers, of which the following is a specification.

My improvements are applicable to diaphragmatic sound producers generally, although shown herein as related more particularly to what are known technically as "sound-boxes" for use in connection with phonographs, important desiderata in the construction of which are (1) the mounting of the stylus bar or needle arm in such manner as to attain free and perfect articulation thereof, which involves the avoidance of dampening of sound by tightness of mount and consequent frictional resistance; and (2) the construction and proportioning of the air chamber and throat plate back of the vibratory diaphragm in such manner as to attain a perfect quality of tone with a maximum volume of sound vibration to be transmitted to the horn.

The invention consists in the construction and arrangement of parts herein described and claimed specifically, distinctive features being the mounting of the yoke of the needle arm between V-edge fulcrums and opposed rockable members seated in cavities having a prescribed relation to the apices of said V-edge fulcrums, and in making the throat plate constituting the back of the diaphragmatic air chamber adjustable with relation to said diaphragm, and in forming it with marginal means of communication with the horn throat in contradistinction to central axial communication therewith as heretofore,—the invention also including certain other details of construction, all for the purposes and reasons hereinafter more fully set forth.

15 In the accompanying drawings,

Figure 1, is a front elevation of a photographic sound box embodying the essential features of my invention;

Fig. 2, is a rear elevation thereof;

Fig. 3, is a side elevation thereof;

Fig. 4, is a side elevation thereof taken at right angles to Fig. 3, and looking toward the needle arm and mount;

Fig. 5, is a central vertical sectional elevation taken upon plane of line 5—5 Fig. 1;

Fig. 6, a like view showing the use of an adjustable throat plate;

Fig. 7, is an elevation of the outer side of the anti-friction ball bearing plate;

Fig. 8, is an elevation of the inner side 60 of said anti-friction ball bearing plate;

Fig. 9 is a sectional detail showing the structure of the mount for the needle arm yoke shown in prior figures of the drawings;

Figs. 10, 11, and 12, show modifications in 65 the form of rockable member opposed to the V-shaped fulcrum of the needle arm mount;

Fig. 13, is a front view of the throat plate shown in Fig. 5, detached from the casing; 70

Fig. 14, is a rear view of the throat plate shown in Fig. 6.

In the drawings B, represents what may be designated as the back or base of the sound box formed with the axial socket b, 75 for attachment to and communication with the throat of a horn or other sound delivery device. D, is the resilient diaphragm mounted peripherally between annular gaskets g, g, preferably of tubular structure as heretofore. The diaphragm D, and its gaskets g, g, are held in place in the casing by the cap plate C, secured to the back plate B, by means of screws s, s.

Interposed between the diaphragm D, and 85 the back plate B, is the throat plate T, forming between it and the inner side of the diaphragm the air chamber a. Heretofore the diaphragm D, has been partitioned off from the base B, by a plate having 90 a central aperture concentric with the center of the diaphragm and of relatively large area coincident with the area of greatest amplitude of vibratory movement of said diaphragm. As a consequence the main volume 95 of air in the chamber a, has been inert and unutilized in an economic sense, practically all the work of the diaphragm having been expended in alternately pulling and pushing a relatively small quantity of air 100 through said central opening, so that the full value of diaphragmatic vibration was not attained and utilized for transmission to the horn. In other words the air in a large annular marginal area in the diaphragm chamber surrounding said central opening in the throat plate was practically undisturbed and inactive, limiting and impairing the tone and volume of sound transmitted to the horn. 105

I obviate this difficulty by so forming my throat plate T, that provision is made only for marginal communication between the air chamber a, and the throat chamber b', which opens into the passage to the horn. It will be conceded of course that the extent of vibration of the portion of the resilient diaphragm D, immediately adjacent to its peripheral support between the annular gaskets g, g, is essentially *nil* and of little or no account in affecting the air in the diaphragm chamber a. Hence by positioning the communicating space t, between the diaphragmatic air chamber a, and the throat chamber b', at the margin of the throat plate T, and between it and the peripheral support of the diaphragm D, I obviously attain the maximum effect of diaphragmatic vibration on the air in said diaphragmatic chamber a, so that practically the whole volume of air contained therein is utilized in augmenting and intensifying the sound waves and transmitting them to the horn,—the closed central area of my throat plate T, being directly opposed to the area of maximum extent of vibration of the diaphragm D, as will be seen more particularly by reference to Figs. 5, and 6, with the result that all fluctuations of pressure created by alternate rarefactions and condensation of such air are communicated with full force to and through the throat chamber b'.

Obviously the communicating space t, may consist of a single annular marginal aperture as in Fig. 6, in which the throat plate is in the form of a centrally supported disk (shown in detail in Fig. 14) or of a plurality of marginal openings as in Figs. 5, and 13, concentric with the center of the plate and diaphragm, the edges of the throat plate being in this arrangement secured between the base B, and the cap C, by the screws s, s, hereinbefore referred to. The advantage of the disk form of throat plate shown in Figs. 6, and 14, is that provision is thereby made whereby the area or capacity of the air chamber a, may be regulated with accuracy to meet the exact requirements of the resilient diaphragm D, used in connection therewith,—such diaphragms varying individually to some extent in flexibility and other inherent qualities which variations may be met or compensated for to a considerable extent by varying the distance between the throat plate T, and the mean or medial position of the diaphragm. This adjustment may obviously be effected by the use of mechanical expedients of different kinds and I do not limit myself in this respect, although the means shown in Fig. 6, is simple and effective, consisting in providing the rear side of the throat disk or plate T, with a screw stud t', which engages a female thread in

the spider web b², in the base B,—a set nut b³, also being provided by means of which the throat plate T, may be secured in a prescribed position with relation to the diaphragm D, as found most expedient by test. 70

In this disk structure of throat plate T, shown in Figs. 6, and 14, an annular plate e, is interposed between the cap C, and the base B, for the support of the gaskets g, g, and diaphragm D. In the structure shown 75 in Fig. 5, the edge of the throat plate T, performs a like function. i, is an annular cushion or gasket interposed between the base B, and the other parts to prevent the transmission metallically as far as possible 80 of mechanical vibration (as the scratching of the needle) through the structure; and for a like reason rubber or similar washers s', s' are interposed between the heads of the screws s, s, and the back plate B. 85

From what has heretofore been said in connection with the means of communication between the diaphragmatic air chamber a, and the throat chamber b', it will be understood that by the use of the term "marginal communication" herein I mean to designate any opening or openings in or created by the throat plate that will answer the purpose in contra-distinction to a throat plate with a central aperture as heretofore. 90

The yoke n, of the stylus or needle arm N, is pivotally supported in a peculiar manner, *i. e.*, between one or more fixed V-shaped knife edged fulcrums f, and an opposed rockable member or members r, 100 conveniently seated. By the use of the rockable member r, directly opposed, in its contactual engagement with the yoke n, to the apex of the V-shaped knife edged fulcrum f, I attain free and untrammelled articulation for 105 the needle arm with a minimum of frictional resistance, since it is obvious that the said rockable member r, while confining the yoke n, adequately against the V-shaped knife edge of the fulcrum, will adapt itself readily 110 to the vibratory motion of the needle arm and yoke without variation of pressure against said fulcrum point. I thus obviate the muffling of vibration incidental to a tight mount and the rattling and slurring 115 incidental to a loose mount, as is apt to occur where spring or trunnion mounts are employed as heretofore, in both of which types of mount very careful assembling and adjustment of parts is necessary in order to 120 attain fair results, whereas by my type of mount the parts may be assembled without the use of skilled labor since the relation of the parts is positively predetermined and fixed, and no adjustment of tension or pressure is necessary. 125

While in a preferable form of my mount an anti-friction roller is used as the rockable member r, as illustrated in sectional detail in Fig. 9, still I do not limit myself thereto, 130

nor to any specific form of rockable member, since the modifications thereof shown in Figs. 10, 11, and 12, or others, may be substituted with like result,—the rocker r , in each case being provided with a concave seat r' , diametrically opposed to the V-shaped knife edge of the fulcrum.

By preference two V-shaped knife edge fulcrums f , are provided, one for each arm 10 of the yoke n , and the opposed rockable members r , are seated in concavities r' , formed for their reception in a common bearing plate r^2 , secured rigidly to the cap C, by screws r^3 , r^3 , as shown more particularly in Fig. 4. The slots in the plate r^2 , through which the shanks of the said screws r^3 , r^3 , pass may be made concentric to a medial point (as shown in Figs. 7, and 8) so that the rocker plate r^2 , may be so adjusted 20 as to impart a slight torsional strain to the needle bar N, if desired, for the purpose of stiffening the diaphragm or action.

What I claim as my invention and desire 25 to secure by Letters Patent is,

1. In diaphragmatic sound producing apparatus of the character designated, the combination with the diaphragm and its casing of a needle arm mount comprising two stationary V-shaped fulcrums, opposed rockable members contacting with the needle arm in alinement with the apices of said fulcrums, a bearing plate formed with concave seats for said rockable members, and means for adjusting said bearing plate on an axis medial between said stationary V-shaped fulcrums for the purpose of impart- 30

ing a torsional strain to the needle arm and diaphragm as set forth.

2. In diaphragmatic sound producing apparatus of the character designated, the combination with the diaphragm and its casing of a needle arm mount comprising two stationary V-shaped knife-edged fulcrums, opposed anti-friction rollers contacting with the needle arm in alinement with the apices 40 of said V-shaped knife-edged fulcrums, and a rigid bearing plate formed with concave seats for said anti friction rollers and movable to impart a torsional strain to the needle arm and diaphragm, for the purpose set forth.

3. In diaphragmatic sound producing apparatus of the character designated, the combination with the diaphragm and its casing of a needle arm mount comprising a plurality of stationary V-shaped knife-edged fulcrums upon and protruding outward from the casing, and diametrically opposed rockable members contacting with the needle 55 arm in alinement with the apices of said protuberant V-shaped knife-edged fulcrums, a rigid bearing plate fixedly attached to the casing and provided with a concavity, said rockable member being movably mounted to 60 impart torsional strain to the needle bar and being seated in said concavity in said rigid bearing plate, for the purpose set forth.

JAMES T. SIBLEY.
